UNITED STATES PATENT OFFICE.

JOHN W. BREWER, OF MAGNA, UTAH, ASSIGNOR OF ONE-HALF TO M. A. WARD, OF MAGNA, UTAH.

RAIL-SUPPORTING DEVICE.

Application filed September 3, 1925. Serial No. 54,258.

To all whom it may concern:

Be it known that I, JOHN W. BREWER, a citizen of the United States, and a resident of Magna, in the county of Salt Lake and State of Utah, have made a new and useful invention in Improvements in a Rail-Supporting Device, of which the following is a specification.

The invention relates to a device which acts as a tie plate, clamp, rail brace and anti-creeper. It has for its principal objects the provision of a cheap simple device for the purpose specified, which can be easily applied and which performs the following functions: (1) prolongs the life of the ties, (2) keeps the track up to a standard gage, (3) prevents the rails from tilting laterally from normal upright position, and (4) keeps the ties properly spaced and prevents the rails creeping due to the tractive effect of the cars or to varying heat conditions causing the rails to expand and contract. A further specific object is the provision of improved means for securing the tie plate to the tie without working loose, and which will permit of the use of the device with ties of varying size. Still other specific objects are the provision of a device which will prevent splitting of the ties by the spikes, which will remove a large part of the holding strain from the spikes, and which can be applied without difficulty to old track without any cutting or boring of the ties. One embodiment of the invention is shown in the accompanying drawings wherein:

Figure 1 is a side elevation of the device in position of use with a rail and tie. Fig. 2 is an end elevation. Fig. 3 is a plan view. Fig. 4 is a plan view of the tie plate taken by itself. Fig. 5 is a side elevation of the clamping wedge or key. Fig. 6 is a plan view of the wedge. And Fig. 7 is a section on the line VII—VII of Fig. 6.

Referring to the drawings, 1 represents the tie plate as a whole, 2 is the rail, and 3 is a wood tie upon which the plate is mounted. The upper face of the plate is depressed slightly over a portion of its area, as indicated at 4 (Fig. 4) to form a seat or recess for the base of the rail and relieve the spikes of some of the strain of holding the rail against a spreading movement. The tie plate is also provided with the perforations 5 (Fig. 4) for the spikes 6, which are driven

into the tie. On one side, the plate is provided with a recurved brace 7, which engages the web of the rail, as indicated in Fig. 1, and supports it against a tilting or spreading movement about its base. This brace is somewhat yielding, so that it springs into position and supports the rail, but at the same time gives enough flexibility to materially decrease the rail wear on curves. 55

At the opposite sides of the plate 1 are the downwardly extending flanges 8 and 9, the flange 9 being parallel to the side of the tie, while the flange 8 is inclined, as indicated in Fig. 3, to correspond to the taper on the outer side of the clamping key 10 (Figs. 3 and 6). The lower edge of the flange 8 is also provided with a ledge or shelf 11 to give a guide or support for the lower edge of the wedge. When the wedge is driven into position, as indicated in Fig. 1, the tie is tightly clamped between the flanges 8 and 9. This clamping action tends to prevent any splitting of the tie by the spikes 6, and also gives the tie plate a secure grip upon the tie independent of the holding effect of the spikes. The spikes are thus largely relieved of the work of holding the tie plate, and as a result do not work loose, as is the case with spikes used with the ordinary tie plate. A further advantage, incident to this secure grip by the tie plate upon the tie, is a reduction of the movement of the tie plate upon the tie, and as a result, the tie plate does not cut down into the tie as would otherwise be the case. 85

A further result is a better maintenance of the track gage, as the tie plates do not work loose and spread, as is the case where all the work is thrown upon the spikes, which soon loosen slightly in the wood and permit the rail to move laterally. The fact that the spikes remain tight also reduces any creeping action of the rails, such as occurs after the spikes loosen their grip upon the rail flanges. 95

In order to increase the gripping effect of the flange 9 upon the tie, the inner face of this flange is roughened, preferably by punching through at a plurality of points to provide the projections 12 (Fig. 2). A similar effect is also secured upon the wedge 10 by providing the teeth 13 upon the side of the wedge next to the tie. The wedge or key is preferably made as indicated in Figs.

5, 6 and 7, being stamped from sheet metal with the flanges 14 and 15 to give it stiffness. It is also provided with the end member 16 for striking with a hammer in driving the wedge into place or loosening it.

The wedge feature also adapts the device to be used with ties of varying width. The flanges 8 and 9 fit loosely over the tie, and the tapering wedge serves to take up the lost motion, so that no cutting of the tie is necessary in order to make the device fit ties of different widths. The tie plate may be readily applied either in laying new track, or in replacing tie plates on track already laid. Other advantages incident to the structure will be readily apparent to those skilled in the art.

It will be understood that the invention is subject to modification, dependent upon conditions of use. The brace 7 may be omitted, when desired, or conditions call for it, and the length of the tie plate varied. Keys of varying thickness may also be used to take care of ties of odd sizes or which have shrunk so that the regulation key is insufficient to make the plate tight.

What I claim is:

1. In combination with a rail and a tie extending transversely therebeneath, of a perforated tie plate between the rail and tie having flanges extending downward along the sides of the tie, one of which is inclined away from the other a tapering wedge having a driven fit between the inclined one of said flanges and the side of the tie, and spikes extending through the perforations in the tie plates and securing the base of the rail down against such plate.

2. In combination with a rail and a tie extending transversely therebeneath, of a perforated tie plate between the rail and tie having flanges extending downward along the sides of the tie, a tapering wedge having a driven fit between one of said flanges and the side of the tie and having teeth on its side next to the tie, and spikes extending through the perforations in the tie plate and securing the base of the rail down against such plate.

3. In combination with a rail and a tie extending transversely therebeneath, of a perforated tie plate between the rail and tie having flanges extending downward along the sides of the tie, with one of such flanges parallel to the side of the tie and the other side inclined with respect to the other side of the tie, a wedge having a driven fit between said inclined flange and the side of the tie and having its side engaging said flange inclined to correspond with the inclination of said flange, and spikes extending through the perforations in the tie plate and securing the base of the rail down against such plate.

4. In combination with a rail and a tie extending transversely therebeneath, of a

perforated tie plate between the rail and tie having flanges extending downward along the sides of the tie, with one of such flanges parallel to the side of the tie and the other side inclined with respect to the other side of the tie, a wedge having a driven fit between inclined flange and the side of the tie and having its side engaging said flange inclined to correspond with the inclination of said flange, and spikes extending through the perforations in the tie plate and securing the base of the rail down against such plate, the side of said wedge next to the tie being provided with teeth adapted to bite into the tie when the wedge is driven into place.

5. In combination with a rail and a tie extending transversely therebeneath, of a perforated tie plate between the rail and tie having flanges extending downward along the sides of the tie, a tapering wedge having a driven fit between one of said flanges and the side of the tie, and spikes extending through the perforations in the tie plate and securing the base of the rail down against such plate, the flange of the tie plate on the side remote from the wedge being provided with projections adapted to bite into the tie when said wedge is driven into place.

6. In combination with a rail and a tie extending transversely therebeneath, of a perforated tie plate between the rail and tie having flanges extending downward along the sides of the tie, one of which is inclined away from the other, a tapering wedge having a driven fit between the inclined one of said flanges and the side of the tie, a recurved brace integral therewith the tie plate and engaging the web of the rail, and spikes extending through the perforations in the tie plate and securing the base of the rail down against such plate.

7. In combination with a rail and a tie extending transversely therebeneath, of a perforated tie plate between the rail and tie having flanges extending downward along the sides of the tie, one of which is inclined away from the other, a tapering wedge having a driven fit between the inclined one of said flanges and the side of the tie, a recurved yielding brace integral with the tie plate and engaging the web of the rail, and spikes extending through the perforations in the tie plate and securing the base of the rail down against such plate.

8. In combination with a rail and a tie extending transversely therebeneath, of a perforated tie plate between the rail and tie having flanges extending downward along the sides of the tie, a tapering wedge having a driven fit between one of said flanges and the side of the tie, and spikes extending through the perforations in the tie plate and securing the base of the rail down against such plate, the portion of the upper face of

the tie plate which is engaged by the base of the rail being depressed so as to form a holding seat or recess for the rail.

9. In combination with a rail and a tie extending transversely therebeneath, of a perforated tie plate between the rail and tie having flanges extending downward along the sides of the tie, a tapering wedge having a driven fit between one of said flanges and the side of the tie, and spikes extending through the perforations in the tie plate and securing the base of the rail down against such plate, the flange of the tie plate which is engaged by the wedge having an inturned shelf or ledge at its lower edge for guiding the lower edge of the wedge.
10. In combination, a tie plate provided with spike holes and having downwardly extending flanges at its side edges, one of which is inclined with respect to the other edge, and a recurved brace at one side of the plate adapted to engage the web of the rail which is seated on the tie plate.

11. In combination, a tie plate provided with spike holes and having downwardly extending flanges at its side edges, one of which is inclined with respect to the other edge, and a recurved spring brace integral with the plate and adapted to engage the web of the rail which is seated on the tie plate.

12. In combination, a tie plate provided with spike holes and having downwardly extending flanges at its side edges, one of which is inclined with respect to the other edge, and a recurved brace at one side of the plate adapted to engage the web of the rail which is seated on the tie plate, the upper face of the plate being recessed transversely to provide a seat for the rail with which the tie plate is used.

In testimony whereof, I have hereunto subscribed my name this 28th day of August, 1925.

JOHN W. BREWER.
